Primary Examiner — Katrina N Gonzalez(57) **CLAIM**

The ornamental design for a pet nail clipper, as shown and described.

DESCRIPTION

FIG. 1 is a perspective view of a pet nail clipper showing our new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is an enlarged detail view of area 9 shown in FIG. 5.

FIG. 10 is an enlarged detail view of area 10 shown in FIG. 6.

FIG. 11 is an enlarged detail view of area 11 shown in FIG. 7; and,

FIG. 12 is an enlarged detail view of area 12 shown in FIG. 8.

FIGS. 6 through 12 show broken lines that represent the boundaries and indicators of the enlarged views. The broken lines form no part of the claimed design.

1 Claim, 12 Drawing Sheets(56)
